TIRE INFLATING PUMP

Filed April 20, 1922

2 Sheets-Sheet 2

UNITED STATES PATENT OFFICE.

THOMAS MORRIS DAVIES, OF LLANELLY, WALES.

TIRE-INFLATING PUMP.

Application filed April 20, 1922. Serial No. 555,668.

To all whom it may concern:

Be it known that I, THOMAS MORRIS DAVIES, a subject of the King of Great Britain, residing at Llanelli, in the county of Carmarthen, Wales, have invented a new and useful Tire-Inflating Pump, of which the following is a specification.

The present invention is an improvement in or modification of the invention described 10 in the specification of Patent No. 1,377,563 dated May 10th, 1921.

The object of the present invention is to construct a pump which is better adapted for carrying upon a motor vehicle than that 15 previously described in my aforesaid specification.

According to one construction of my previous invention, the laterally extending base and the inclined stays connecting the base 20 to the standard were adapted to fold up with the two members as nearly as possible in alignment with the standard and pump barrel. These two parts of the base both folded upwardly and when they were moved 25 downwards into their position for use the outer ends were connected by means of thumb screws.

According to the present invention the two stay rods are pivoted at their upper 30 ends to a bridge piece connecting the two sides of the standard so that they may fold downwards parallel to the standard and at their lower ends they are provided with spring clips which engage with sleeves 35 upon a cross piece connecting the two sides of the standard at the extreme lower end thereof. The pump barrel is pivoted to the said cross piece. In addition to the spring clips the stay rods are provided at their 40 lower ends with laterally projecting pins which are preferably provided with heads. Each side of the base carries a slotted plate, the slot of which is adapted to receive one of the headed pins carried by the stay rods. 45 The base is also provided with two portions of a strap so that when the whole apparatus is folded the base may be retained close to the standard and the strap may be passed around the hand lever of the pump thereby 50 retaining this latter close to the pump barrel.

The upper portion of the standard is preferably provided at each side with a spring clip to receive two portions of the air delivery tube, which is bent towards its 55 outer end so that two parts thereof may en-

ter the spring clips and the tube will not project beyond the end of the standard.

The invention is illustrated in the accompanying drawings in which Fig. 1 is a side elevation of the apparatus erected for use 60 and Fig. 2 is a plan of the lower part thereof shown partly in section. Fig. 3 is a side elevation showing the parts folded for transport. Fig. 4 is a front elevation seen in the direction of the arrow 4 of Fig. 1. Fig. 5 65 is a front elevation of the upper part of the apparatus showing the air delivery tube retained by the clips. Fig. 6 is a detail view to an enlarged scale showing a modification.

a is the main standard of the pump, which 70 is connected at its lower end by the cross piece *a*¹ and is provided with a bridge piece *a*². *b* is the base pivoted at *b*¹ to the standard *a* and provided at each side with a slotted plate *c*. To each side of the base *b* 75 is connected one part of a strap *d* by which the parts may be retained in their folded position, as shown in Fig. 3. *e*, *e* are the inclined stay rods pivoted at their upper ends at *e*¹ to the bridge *a*². These stay rods *e* are 80 provided at their lower ends with laterally extending pins *e*² which are preferably provided with heads and are adapted to enter a slot *c*¹ in each plate *c*. The inclined stay rods *e* are connected together at their lower 85 ends as in my previous invention and they are provided with spring clips *f* adapted to engage with sleeves *a*³ surrounding the cross piece *a*¹. The handle *g* is attached to one side of the standard *a*. Two spring clips *h* 90 are fixed to the standard *a* to receive two portions of the air delivery tube *i* which is bent into a curve near to the handle *g* as shown in Fig. 5. When it is desired to use the pump the strap *d* is unfastened and the 95 pins *e*² are moved along the under side of the base *b* until they arrive at the wider portion thereof, when they can be passed upwards onto the upper surface of the base *b* and be inserted into the slots *c*¹ of the 100 plates *c*. As the pump is rocked on the foot *b*² and as downward pressure is always applied to the standard *a* in the act of pumping the pins *e*² automatically remain at the 105 ends of the slots *c*¹.

When it is desired to fold the pump for storage the pins *e*² can be readily withdrawn from the slots *c*¹ and be moved backwards over the upper part of the base *b* and passed through the wider portion thereof, after 110

which the stay rods e are moved on their pivots e^1 until the spring clips f engage the sleeves or distance pieces a^3 mounted on the cross piece a^1 . The stay rods e may be 5 slightly cut away at e^3 to enable them to be rocked sufficiently to enable the pins e^2 to pass over the plates e and through the wider portions of the base b . It is obvious that 10 the spring clips f may engage direct with the cross piece a^1 if the sleeves or distance pieces a^3 be omitted. j is the pump barrel pivoted at its lower end on the cross piece a^1 and k is the hand lever pivoted at its upper end at k^1 to the standard a . The hand lever 15 k is pivoted at k^2 to a casting k^3 fixed to the upper end of the pump rod k^4 .

Although there is no tendency for the pin e^2 to leave the slot c^1 in the act of pumping it may happen that the pump when standing as shown in Fig. 1 receives a blow in the opposite direction to the arrow 4, in which case the pin e^2 may slide along the slot c^1 and the pump may then topple over. The pin e^2 may also leave the slot if the pump is 20 dragged along the ground by the handle g or by the hand lever k . In order to prevent the pin e^2 leaving the slot c^1 this latter may be cut away at the top and bottom thereof at c^2 , as shown in Fig. 6, in which case the 25 pin e^2 will normally rest in the lower part which has been cut away. Should, however, the pump be lifted by the handle g , the pin e^2 will then probably rise into the upper part which has been cut away at c^2 . In 30 Fig. 6 I have also shown the slot c^1 as tapered, thus enabling the pin e^2 to readily enter the mouth of the slot but to be a good fit towards the inner end thereof, which further reduces any tendency for the pin e^2 to 35 leave the slot c^1 . Further a certain amount of friction may be applied at the pivotal points e^1 to prevent the stay rods e moving too freely. Such friction may be produced 40 by causing the stay rods e to bear outwards 45 against the inner faces of the bridge piece a^2 .

What I claim as my invention is:—

1. An improved air pump having in combination a standard, a pump barrel pivoted at its lower end to the standard, a hand lever pivoted at its upper end to the standard and connected intermediate of its ends to the pump rod, a base pivoted to the standard, 50

plates carried by the sides of the base, a slot in each of said plates, a bridge piece carried by the standard, stay rods pivoted to 55 said bridge piece and pins, carried by the lower end of the stay rods, adapted to enter the slotted plates carried by the base, substantially as set forth.

2. An improved air pump having in combination a standard, a pump barrel pivoted at its lower end to the standard, a hand lever pivoted at its upper end to the standard and connected intermediate of its ends to the pump rod, a base pivoted to the standard, plates carried by the sides of the base, a slot 60 in each of said plates, a portion cut away at the top and bottom at the inner end of said slot, a bridge piece carried by the standard, stay rods pivoted to said bridge piece and pins, carried by the lower end of the stay rods, adapted to enter the slotted plates carried by the base, substantially as set forth. 65

3. An improved air pump having in combination a standard, a pump barrel pivoted at its lower end to the standard, a hand lever pivoted at its upper end to the standard and connected intermediate of its ends to the pump rod, a base pivoted to the standard, plates carried by the sides of the base, a slot 70 in each of said plates, a bridge piece carried by the standard, stay rods pivoted to said bridge piece and pins, carried by the lower end of the stay rods, adapted to enter the slotted plates carried by the base, substantially as set forth. 75

4. An improved air pump having in combination a standard, a pump barrel pivoted at its lower end to the standard, a hand lever pivoted at its upper end to the standard and connected intermediate of its ends to the pump rod, a base pivoted to the standard, plates carried by the sides of the base, a slot 80 in each of said plates, a bridge piece carried by the standard, a cross piece connecting the lower ends of the standard, sleeves thereon and spring clips carried by the lower ends of the stay rods adapted to engage said sleeves, substantially as set forth. 85

4. An improved air pump having in combination a standard, a pump barrel pivoted at its lower end to the standard, a hand lever pivoted at its upper end to the standard and connected intermediate of its ends to the pump rod, a base pivoted to the standard, plates carried by the sides of the base, a slot 90 in each of said plates, portions of a strap carried by said base and adapted to retain the base in its folded position, a bridge piece carried by the standard, stay rods pivoted to said bridge piece and pins carried by the lower end of the stay rods adapted to enter the slotted plates carried by the base, substantially as set forth. 95

In witness whereof I have set my hand.

THOMAS MORRIS DAVIES.
